UNITED STATES PATENT OFFICE.

CLIFFORD W. COWLES, OF NEW BRITAIN, CONNECTICUT, ASSIGNOR TO GROUNDELET COMPANY, OF NEWARK, NEW JERSEY, A CORPORATION OF NEW JERSEY.

ELECTRICAL CONNECTION.

Application filed August 16, 1922. Serial No. 582,372.

To all whom it may concern:

Be it known that I, CLIFFORD W. Cowles, citizen of the United States, residing at New Britain, in the county of Hartford and State of Connecticut, have invented certain new and useful Improvements in Electrical Connections, of which the following is a specification.

This invention relates to an electrical connection, or connecting device, the principal object of the invention being to provide a structure which is quite simple and the parts of which can be readily assembled and by which a ground connection either in or out 10 of a building or dwelling, can be easily accomplished, it being a difficult matter at the present time as I understand to make such a ground connection with for instance a water pipe and by which no injury to the 20 connection is possible.

In the drawing accompanying and forming part of the present specification, I have shown in detail a form of embodiment of the invention which to enable those skilled 25 in the art to practice the same will be set forth fully in the following description. Clearly I am not restricted to this disclosure. I may depart therefrom in a number 30 of respects within the scope of the invention defined by the claims following said description.

Referring to said drawing:

Fig. 1 is a top plan view.

Fig. 2 is a longitudinal section, the pipe 35 being shown in section.

Fig. 3 is a cross section on the line 3—3 of Fig. 1.

Like characters refer to like parts throughout the several views.

It is a difficult matter as I know from a 40 variety of causes to make the ground connection, of a service cable or wire or conductor with a water pipe, which is generally utilized for the ground. I provide a 45 construction by which such a connection can be made in a rapid and efficient manner.

The connecting device involves in its 50 make-up a duct or connector member such as that denoted in a general way by 2 and 60 which is generally of channel or gutter formation, but which may if desired be closed on the upper side after an installation or connection has been made. This duct member or connector, preferably con-

sists of a rigid portion and a resilient portion, both usually being constructed of metal, although the connector may be constructed of any desired material as long as there is a suitable arrangement made to electrically connect the conduit and the electrical conductor to the pipe or grounded element. The rigid portion has at the outer end of its gutter or channel portion, a connecting head 3 and which is usually tubular and which is provided with means by which a suitable 65 connection or joint may be made with a pipe or conduit, tube or other carrier for the cable or wire or electrical conductor. For the purpose, the tube or pipe 4 is shown, the forward end of the pipe being detachably 70 fitted as by threading, into the tubular head 3.

The means shown for mechanically and electrically connecting the duct member 3 with a water pipe or other grounded element may be of any suitable character, the flexible clip 5 being shown for the purpose.

This flexible clip or strip 5, like the duct member 2, is of electrically conducting material. The clip or flexible portion 5 has 80 a comparatively straight shank or tongue 6 which is thrust into the longitudinal seat 7 of duct member 2, thereby providing an extended electrical contact between the tongue strip and member 2. Clip 5, as I 85 will explain hereinafter in detail, is connected electrically with duct member 2 as by a bolt or screw 10. In assembling the parts, the free portion 8 of clip 5 is wrapped or coiled partially around water pipe 9 as 90 shown in Figs. 2 and 1. As shown in these figures, the end of duct connector 2 abuts against pipe 9, thereby providing a mechanically rigid construction. After the flexible portion of clip 5 has been passed around water pipe 9 (or other pipe or other grounded element), its free end 8 is rigidly connected to duct connector 20 by the screw or bolt 10, the shank of which projects through a perforation in the tongue or shank 6 of clip 5, the threaded end of the screw or bolt 10 being fitted in registering threaded openings in seat-members 7 of connector duct 2. Thus the threaded part of screw or bolt 10 passes through and is in screw-threaded connection with shank or tongue 6 of clip 5, and also is firmly connected with trough or duct member 2.

It will be assumed that the pipe or conduit 4 is in threaded or other connection with the head 3 of connector duct 2 shown in Figs. 1 and 2 with set screw 15, and that a ground connection is to be made with a water pipe as 9 or other grounded element. The free flexible portion 8 of clip 5 will be partially passed around grounded element 9. Then bolt or screw 10 will be applied, so as to pull clip 5 tightly around pipe 9 and pull duct member 2 against pipe 9, thereby coupling connector duct 2 with grounded element 9 and also electrically connecting said parts. The cable, wire or lead 11, passed through the pipe or conduit 4, will be connected to tip-piece 13 constituting attaching means for said lead 11. Another part of lead-attaching means 13 is connected to end 8 of clip 5 as by a screw 14. Since clip-end 8 has been connected by screw or bolt 10 to seat-parts 7 of connector duct 2, therefore lead 11 will be mechanically and electrically connected with connector duct 2 as well as with clip 5. Thus, since duct 2 and clip 5 are in tight connection with pipe 9, lead 11 by way of said members 2 and 5 will be in good electrical connection with pipe 9. Thus when lead 11 is connected up inside duct member 2, there will be a perfect ground connection for both the lead 11 and conduit 4.

Cable 11 may be electrically and mechanically connected to the inside of duct member 2 in various ways. For example, as shown, when part 13 of conducting material is provided inside duct member 2, cable 11 will be skinned to enter 13 as shown, and part 13 may be connected to end 8 of clip 5 as by the screw 14 shown. The device 10 shown serves to make a good electrical connection of cable 11 to the conducting material of duct member 2, so as to secure the ground connection to which I have referred between cable 11 and pipe 9. Thus irrespective of the means by which duct member 2 is secured in good contact with part 9, cable 11 is well grounded to 9 without being in direct contact therewith. This permits duct member 2 to be secured to pipe 9 independently of the connection of cable 11 to duct member 2; that is, it permits the connection of cable 11 to the interior of duct member 2 to be made independently of the connection of duct member 2 to pipe 9. From the above description, it will be apparent that the lateral opening in duct member 2 permits the connection of cable 11 to the interior of the duct member, and said opening permits inspection of the connection at any time thereafter; while the walls of duct member 2 serve to protect cable 11 and its attaching means against movements of objects brought near them. The electrical connection of cable 11 to the accessible but protected interior of duct member 2, by way of devices 6, 7, 8, 10, 13 and 14, causes this portion of the construction to

be independent of the particular means which may be employed to secure duct member 2 to pipe 9, which means in the drawings involves electrical connection of both clip 5 and the end of duct member 2 with pipe 9. Thus while in any case I may employ a duct member with cable 11 and with the attaching means for the cable inside duct member 2 and in good electrical connection with the conducting material of duct member 2, yet any suitable means generally equivalent to clip 5 may be employed for securing duct member 2 itself to pipe 9 in good electrical and mechanical connection therewith, such equivalent means being any of those known in the art, such as a clamp, or a screw coupling as 3, as alternative to the clip or strap 5 shown.

The connector duct 2, with interior means for attaching the cable thereto, and constructed with the lateral opening shown, may be interposed between any two parts of a grounding system; and for that purpose its two ends may be constructed in any manner suitable for permitting such interposition and to permit said ends to be connected securely, mechanically and electrically, to the ends of the grounding system in which duct member 2 is to be interposed. As shown, duct member 2 is connected at the left to the conduit 4, which protects cable 11, and to the cable itself, respectively; but at the right cable 11 is not directly connected to pipe 9, for the electrical connection between cable 11 and pipe 9 is by way of connector 2 itself and the means by which connector 2 is secured to pipe 9. And, as suggested above, this freedom of direct connection between cable 11 and pipe 9 is obtained by the provision inside connector duct 2 of means for making good electrical connection between cable 11 and connector duct 2.

It will be seen from the foregoing descriptions that there are several important advantages in my improved apparatus for grounding an electrical system together with a conduit system inside which the electrical conductors are carried. Although I have illustrated in the drawing only a portion of one conduit (4) and a portion of a grounding pipe or ground element (9) and a portion of an electrical conductor (11), I desire to be understood as meaning that said portions of each of said conduit, pipe or grounded element and conductor are parts of the usual complete electrical and conduit systems. It is my main intention that a proper and advantageous ground connection may be had for the conduit system and for the electrical system. The connecting of the electrical conductor (as 11) to a water pipe system or ground element generally is considered as being a proper grounding connection in the home, but in central power plants and factories it is advisable to drive one or

more long metal pieces into the earth and connect the electrical conductor and the conduit system to such grounded elements.

The main advantage of the connecting device illustrated is that a sturdy connector of large current-carrying capacity is held in positive engagement with the water pipe (or other grounded element) and a part of such connector is placed under tension to such a degree that vibrations in the central power station, manufacturing plants or in the home are not sufficient to loosen the positive engagement with the grounded element. Another advantage is that the large area of metal contact between conductors of large current-carrying capacity permits the grounding of a heavy current without the metal being fused or burned so that it separates and destroys the value of the grounding connection.

In the usual wiring constructions, substantially all of the cables or conductors are placed within conduits which form a conduit system, and my improved apparatus illustrates the grounding of one of the conduits of such a conduit system. Should there be a grounding of a heavy current which would melt or fuse the conductor or cable, the conduit, being properly grounded, would carry the current to the ground by reason of the melted ends of the conductor falling into contact with the conduit.

My construction is believed to be mechanically and electrically as nearly perfect as possible for its purpose, the only possible defect being that its metal contacting parts are liable to rusting; but anti-rust dipping or coating, frequent in electrical apparatus, will make the device as nearly perfect as possible, maintaining good contact and prolonging life of the device.

The preferred construction of the connector provides an opening which permits inspection of the connection to the connector of the conductor extending through the conduit. This provision complies with one of the requirements of the Fire Underwriters' rules.

It will, therefore, be seen that my type of ground connector protects the electrical system which is to be grounded and also the conduit system itself; and that the connector is of such construction that the mechanical connection with the water pipe or other grounded element prevents loosening due to jarring or other like disturbances. The Underwriters in substantially every State require that the conduit system as well as the electrical system shall be grounded, and it will be observed that my improved unitary connector readily meets these requirements.

It will be understood that while I have herein described in detail a particular embodiment of my invention for purposes of

full disclosure, and some detailed features which I am specifically claiming for special advantage, many changes and modifications may be made in the particular construction and arrangement of parts without departing from the broad scope of my invention which is outlined in the claims.

What I claim is:

1. In an electrical grounding system, the combination with a conducting conduit, of a conductor lead, and a conducting pipe, of a conducting duct member formed with a lateral opening and having means for mechanically and electrically connecting its ends to the conduit and pipe of such systems; and attaching means for said conductor lead, said attaching means being mounted inside the duct member, in electrical connection therewith and in position accessible and visible through the lateral opening of the duct member.

2. An electrical connector comprising a conducting duct member formed with a lateral opening, in combination with lead-attaching means located inside the duct member in position accessible and visible through said lateral opening; and a flexible metal clamping strip secured in extended contact with the duct member near one end thereof and electrically connected with said lead-attaching means; and means on the other end of the duct member to connect it electrically and mechanically to a suitable conducting member.

3. A device for connecting a conduit system and an electrical system to a grounded element, whereof the conducting conduit system encloses a conductor of said electrical system, said connecting device comprising a channeled body portion provided with means for mechanically and electrically connecting it with a grounded element of such system, and provided with means for making mechanical and electrical connection with a conducting conduit of said conduit system; said channeled body portion being also provided with means for making electrical connection with an end of the conduit-enclosed conductor; and said channeled body portion being provided with means establishing mechanical and electrical connection to the grounded element.

4. In a ground connection, a connecting device comprising a rigid portion and a flexible portion assembled together end to end; one end of the flexible portion being left free to engage a conducting pipe, one end of said rigid portion being left free and constructed to receive an end of a conducting conduit; said connecting device including means for electrically connecting said rigid portion to an end of an electrical conductor which passes through the conduit.

5. In a ground connection, a connecting device comprising a rigid portion and a

- flexible portion assembled together end to end, one end of the flexible portion being left free and wrapped around a conducting pipe and in electrically contacting engagement with a part of said rigid portion; one end of said rigid portion being left free and constructed to receive an end of a conducting conduit; and means for firmly affixing to said rigid portion said free end of the flexible portion; said connecting device including means for electrically connecting to said rigid portion an end of an electrical conductor which passes through said conduit.
6. In a ground connection, a connecting device having a flexible portion and a relatively long rigid portion; means for connecting said flexible portion and one end of said rigid portion mechanically and electrically to one and the same conducting pipe; and means electrically connecting to said rigid portion a conductor leading from an electrical system.
7. In a ground connection, a connecting device comprising a rigid portion and a flexible portion assembled together end to end, one end of said flexible portion being left free and wrapped around a grounded element and brought back into contact with said rigid portion; means for affixing said free end of said flexible portion to the rigid portion, said rigid portion having a part engaging said grounded element and another part thereof constructed to receive a part of a conduit which carries electrical conductors.
8. In a ground connection, a connecting device comprising a flexible portion engaging a conducting pipe and a rigid portion to which one end of the flexible portion is secured; means for affixing the other end of said flexible portion to the rigid portion; said rigid portion being of channel shape and provided at one end with a curved portion engaging the curved surface of said conducting pipe and provided at the other end thereof with means for making mechanical and electrical connection with a conducting conduit which encloses an electrical conductor and a lead-attaching device mounted inside the channeled rigid portion in electrical connection therewith.
9. In a ground connection, a connecting device comprising a rigid portion and a flexible portion assembled together end to end, said flexible portion being wrapped around a grounded element and having its free end in contacting engagement with the rigid portion; means for fastening said free end of the flexible portion to the rigid portion; said rigid portion being of channel formation and having its free end constructed to receive the end of a conduit which carries electrical conductors; an electrical conductor leading from an electrical system to and through said conduit to said rigid portion of the connecting device; and means for fastening said conductor to said rigid portion within the channel thereof.
10. In a ground connection, a connecting device comprising a rigid portion and a flexible portion assembled together end to end, said flexible portion being wrapped around a grounded element and having its free end in contacting engagement with said rigid portion, said rigid portion being substantially of channel formation having provided at one end thereof an annularly closed part arranged to receive therewithin the end of a conduit carrying electrical conductors; means for firmly affixing said conduit to said rigid portion; and a lead-attaching device mounted inside the channeled rigid portion and the other end of said rigid portion adjacent the flexible portion having conforming engagement with the grounded element in co-operation with said flexible portion.
11. In a ground connection, a connecting device comprising a rigid portion and a flexible portion assembled together end to end, said flexible portion being wrapped around a grounded element and having its free end in contacting engagement with the rigid portion; said rigid portion being substantially of channel formation, having provided at one end thereof an annularly closed part arranged to receive therewithin the end of a conduit carrying electrical conductors; means for firmly affixing said conduit to said rigid portion; and a lead-attaching device mounted inside the channeled rigid portion and means for firmly affixing the free end of said flexible portion to said rigid portion and simultaneously conforming said flexible portion to the grounded element and causing it to be drawn into tight engagement therewith.
12. In a ground connection, the combination with a connecting device comprising a rigid portion of channel shape having one end closed circumferentially, and a flexible portion secured to the rigid portion and having a free end; of a grounded element; said flexible portion being wrapped about the grounded element to make electrical contact therewith and having its free end in contacting engagement with said rigid portion within the channel part thereof; means for fixing said free end of said flexible portion to said rigid portion, causing said flexible portion to be placed under tension around said grounded element, thereby mechanically fastening the connecting device firmly to said grounded element; a conduit for carrying electrical conductors fastened within the circumferentially closed end of said rigid portion; and an electrical conductor leading from said conduit into the channel part of said rigid portion and electrically connected to said rigid portion.

13. In a ground connection adapted to ground a conduit system and an electric system, the combination of an electrically conducting connector comprising a rigid metal portion and a flexible metal portion, the flexible portion being arranged to engage positively a grounded metal element; one end of said rigid metal portion being held in engagement with said grounded element; a conduit carrying electrical conductors and being one of a series of conduits of a conduit system; said conduit having one end thereof in positive engagement with the free end of the rigid portion of said connector, thereby forming a ground connection for the conduit system; an electrical conductor leading from an electrical system and means for connecting said conductor to said connector, thereby forming a ground connection for the electrical system.
14. An electrical connector comprising a conducting duct member formed with a lateral opening, in combination with lead-attaching means located inside said duct member in position accessible and visible through said lateral opening; means at the ends of the duct member for mechanically and electrically connecting it with the electrical conductors desired to be connected; all in combination with a metal strip in extended electrical contact with the duct member and in electrical connection with said lead-attaching means.
15. In a ground connection, the combination with a connector having a rigid portion thereof of channel shape and having another portion which is flexible, means for mechanically affixing said flexible portion under tension to a conducting pipe; of a conduit for carrying an electrical conductor and held in firm engagement with the rigid portion of said connector; an electrical conductor leading from an electrical system and passing through said conduit into the channeled part of said rigid portion of said connector; and means for electrically connecting said conductor to the rigid part of said connector.
16. In a ground connection, the combination of a connector comprising a hollow rigid portion and a flexible portion assembled together end to end; said flexible portion being in firm engagement with a grounded element, thereby forming an electrical and mechanical association of said connector with said grounded element; a conduit in coupled relation with said rigid portion of the connector; an electrical con-
- ductor leading from an electrical system and located within said conduit and within the hollow rigid portion of said connector; a tip mechanically and electrically connected within and to the rigid portion of said connector; and means for electrically connecting said conductor to said tip.
17. In a ground connection, the combination of a connector comprising a rigid portion and a flexible portion assembled together end to end, said flexible portion and said rigid portion being co-operatively fastened electrically and mechanically to a grounded element; said rigid portion being of channel shape except at its free end where it is closed circumferentially forming a cylindrical head; a conduit leading from a conduit system and arranged to engage said cylindrical head, a set screw for removably holding said conduit in said cylindrical head; an electrical conductor leading from an electrical system; said rigid portion of the connector and said conduit co-operatively receiving and holding said electrical conductor; and a tip electrically and mechanically connected with said conductor and with the rigid portion of said connector.
18. An electrical connector comprising a conducting duct member formed with a lateral opening in combination with lead-attaching means mounted inside said duct member in position protected by the walls of the duct member but accessible and visible through the lateral opening of the duct member; said duct member and lead-attaching means being electrically connected together; and means at the ends of the duct member for mechanically and electrically connecting it with the electrical conductors which are desired to be connected.
19. An electrical connector comprising a conducting duct member formed with a lateral opening in combination with lead-attaching means located in the interior of the duct member in position accessible and visible through said lateral opening; and means at the ends of the duct member for mechanically and electrically connecting it with the electrical conductors desired to be connected; all in combination with means electrically and mechanically uniting the duct member and said lead-attaching means.

In testimony whereof, I hereby affix my signature.
